UNITED STATES PATENT OFFICE.

NICOLAY KNUDTZON FOUGNER, OF CHRISTIANIA, NORWAY.

SEA-MINE OF STEEL-CONCRETE.

1,275,894.

Specification of Letters Patent. Patented Aug. 13, 1918.

Application filed December 6, 1917. Serial No. 205,877.

To all whom it may concern:

Be it known that I, NICOLAY KNUDTZON, FOUGNER, a subject of the King of Norway, residing at Christiana, in the Kingdom of Norway, have invented certain new and useful Improvements in Sea-Mines of Steel-Concrete; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The present invention has for its object a sea-mine (floating mine or submarine mine) of steel concrete and a process for manufacturing the same.

Applicant has found that it is possible to construct hollow bodies of steel concrete which answer to all the requirements with regard to strength, buoyancy and watertightness necessary for sea-mines and submarine mines in particular. In accordance with the invention the hollow mine bodies are produced by means of a lathing of metal net or perforated sheets of metal, mounted on a form of metal or wood. On the outside of the metal lath is placed a layer of cement or the like, to which is added materials adapted to make the cement watertight. Before this layer of plaster is completely hardened, a wire armament is wound in the form of a spiral- or a screw line around the mine body, and this steel wire armament will be partly embedded in the plaster, forming the exterior surface of the mine. After this armature has been placed in position, a further layer of mortar or the like is added to the mine, and the interior of the mine body is also supplied with a layer of cement or the like or painted with a suitable paint or tar.

The invention further comprises means for fastening the charge box and the cables and a number of other details which will be specified in the following.

On the drawing Figure 1 illustrates the main part of the mine body in course of construction.

Fig. 2 is a section through the finished mine, and Fig. 3 illustrates on a smaller scale a modified form of fastening the cables.

As seen on Fig. 1 the metal lath forming

the main armament of the mine walls is mounted on the inner side of a framework 2, consisting of steel rods, said framework and lathing being kept in position by means of exterior wood framing 3. The upper part of the steel rods 2 is bent outwardly, so that the mine body is open at the top. After the armament has been put in position as shown on Fig. 1, the mine body is plastered on the outside and the charge box is put in position as illustrated on Fig. 2. Said charge box 4 is supported by two bars 5, 6, which are placed crosswise at the bottom of the charge box and the undersides of which are curved to fit the inner surface of the mine body. In order to distribute the weight of the charge box as evenly as possible along the bars, cross bolts 7 are provided between the extreme ends of the bars, preventing the same from expanding laterally when exposed to stress. The bars 5, 6, are cast with their under sides to the interior surface of the mine body by means of concrete 8, the charge box being mounted in its exactly correct position through the hardening of this concrete.

The upper side of the charge box is fastened to the mine body by means of stays 9, the upper ends of which are fastened to the wall of the mine body in the same manner as the bars 5, 6. By fastening the charge box in this manner, the mine body is nowhere perforated, so that all causes for leakage are obviated. The interior of the mine body may conveniently be coated with tar or similar material. The upper part or cover 10 of the mine body consists of metal netting or rib lath, which may be provided on its interior surface with a thin layer of plaster 11 and which is also provided with the usual opening 12 for the covering cap of the mine. Along the interior edge of said opening an iron- or metal ring 13 is fastened before the cover 10 is put in place on the mine body, said metal ring 13 being provided with bolts 14, projecting through the wall and serving to fasten the frame for the covering cap.

The top part 10 of the mine body is now put in place, and the armament rods 2 are thereupon bent down upon the same, whereupon it is plastered in the same manner as the main part of the mine body. When this operation has been performed, the steel wire armament 15 is wound in a screw line around the whole mine body, and a second

layer 16 of plaster is added outside this armament. The cap frame 17 is fastened by means of bolts 14.

Outside the mine body is now placed a 5 steel rod or hoop 18, the upper ends of which may conveniently be fastened to the cap frame 17. Said steel hoop 18 is provided with eyes 20, 21, serving to fasten the anchor and carrying cables 22, 23. Said 10 cables may, however, also be fastened in the manner illustrated on Fig. 3, by means of two rings 24, 25, placed at a certain distance on opposite sides of the equatorial plane of the mine. The upper ring is connected to the anchor cable 22, while the 15 lower ring is connected to the float cable or carrying cable 23. The forked ends of both cables may suitably be guided through eyes in the fastening ring for the 20 other cable. A fender consisting of a thick rope 26 or the like may be placed around the equator of the mine body. By constructing the mine as above described, all stresses on the mine are distributed over 25 the largest possible surfaces without perforating the mine wall at any point exposed to stress.

I claim:

1. Sea-mine the walls of which consist 30 of metal lathing, covered by watertight mortar or concrete and further provided with a suitable armament of steel rods, the mine containing a charge box and having fastening bolts for the anchor and carrying 35 cables, the charge box and bolts being fastened to the mine body without perforating the same.

2. Sea-mine the walls of which consist 40 of metal lathing, covered by watertight mortar or concrete and further provided with a suitable armament of steel rods, a charge box mounted on hoops cast to the interior of the mine wall, stays for said charge box the outer ends of said stays being also cast to 45 the inside of the mine wall.

3. Sea-mine the walls of which consist 50 of metal lathing, covered by watertight concrete and further provided with a suitable armament of steel rods, a charge box mounted on hoops cast to the interior of the mine wall, said hoops being provided with cross rods in order to prevent lateral expansion of the same and distribute the pressure 55 equally over the whole length of the hoops.

4. A sea-mine, comprising metal lathing, rods surrounding the lathing, a concrete covering on the lathing and rods, and a

metal hoop on the covering and provided with eyes adapted to receive the anchor and carrying cables. 60

5. A sea-mine comprising metal lathing, metal rods surrounding the lathing, a cap frame to which the lathing and rods are secured, and concrete covering for the whole and having spirally arranged wire embedded therein. 65

6. A sea-mine comprising metal lathing, a skeleton metal frame surrounding the lathing, a layer of concrete on the frame and shell and having spirally arranged wire embedded therein, an outer layer of concrete, and a steel hoop on the outside of the mine and provided with eyes for receiving the anchor and carrying cables. 70

7. In the process of producing mines, the 75 forming of the body of the mine by applying metal rods upon metal lathing with the rods projecting above the lathing, and applying concrete upon the lathing and the portions of the rods below the upper end 80 of the lathing.

8. The herein described process of producing sea mines, consisting in applying a skeleton metal frame having outwardly bent ends upon metal lathing to form the body 85 of the mine, applying a top to the body, bending the ends of the frame upon the top, and applying reinforced concrete upon the body and top.

9. The herein described process of producing sea mines, consisting in applying a skeleton metal frame having outwardly bent ends upon lathing, with said ends projecting above lathing, to form the body of the mine, applying a metal top having an opening 95 upon the body, bending the ends of the frame upon the top, and applying reinforced concrete upon the body and top.

10. The herein described process of producing mines, consisting in applying a series of metal rods upon a metal lathing with the ends of the rods projecting above the lathing to form the body of the mine, applying a metal cover upon the body, bending the rods on the cover, and applying concrete 100 upon the whole. 105

In testimony that I claim the foregoing as my invention, I have signed my name in presence of two subscribing witnesses.

NICOLAY KNUDTZON FOUGNER.
